(57) **CLAIM**

The ornamental design for a spectacle case, as shown and described.

DESCRIPTION

FIG. 1 is a front perspective view of embodiment 1, showing my new design;

FIG. 2 is a rear perspective view of embodiment 1;

FIG. 3 is a front view of embodiment 1;

FIG. 4 is a rear view of embodiment 1;

FIG. 5 is a left side view of embodiment 1;

FIG. 6 is a right side view of embodiment 1;

FIG. 7 is a top view of embodiment 1;

FIG. 8 is a bottom view of embodiment 1;

FIG. 9 is a front perspective view of embodiment 1 in its open state;

FIG. 10 is an enlarged detail view of area 10 in FIG. 1;

FIG. 11 is an enlarged detail view of area 11 in FIG. 2;

FIG. 12 is a front perspective view of embodiment 2;

FIG. 13 is a rear perspective view of embodiment 2;

FIG. 14 is a front view of embodiment 2;

FIG. 15 is a rear view of embodiment 2;

FIG. 16 is a left side view of embodiment 2;

FIG. 17 is a right side view of embodiment 2;

FIG. 18 is a top view of embodiment 2;

FIG. 19 is a bottom view of embodiment 2;

FIG. 20 is a front perspective view of embodiment 2 in its open state; and,

FIG. 21 is an enlarged detail view of area 21 in FIG. 13.

The broken lines in the drawing illustrate environmental structure associated with the spectacle case in a condition of use. The broken lines and structure they depict form no part of the claimed design.

1 Claim, 21 Drawing Sheets
